ELECTRICAL BURGLAR ALARM SYSTEM

Burnett Menkin, New York, N. Y.

Application March 2, 1951, Serial No. 213,649

19 Claims. (Cl. 177—314)

1

This invention relates to improvements in electrical burglar alarm systems, and it relates more particularly to a signal or alarm system responsive, when in operative or set condition, to the movement of doors, windows, or the like, having protective switches associated therewith.

The principal object of the present invention is to provide an electrical burglar alarm system of the type which may be finally set by the closing of a door, whereby the last person to leave a protected building may place the system in operative condition by the mere closing of the exit door as he leaves the building.

A further object of the present invention is to provide a burglar alarm system of the character aforesaid, having improved means for rendering the various alarm circuits operative by the final closing of the exit door.

A further object of the invention is to provide a burglar alarm system of the character aforesaid having a key operated lock by means of which the system may be rendered inert during the normal occupancy and use of the protected building, having improved means whereby the system may be partially set preliminarily to the final closing of the door which will complete the setting thereof.

A further object of the invention is to provide a burglar alarm system of the character aforesaid, having improved means for insuring the retention of the relay armature in the position for maintaining the alarm circuit open during the preliminary setting of the system.

A further object of the invention is to provide improved means in a burglar alarm system of the character aforesaid for indicating faults in the various circuits.

The nature and characteristic features of the invention will be more readily understood from the following description, taken in connection with the accompanying drawings forming part hereof, in which:

Figure 1 is a diagrammatic view of a burglar alarm system embodying the main features of the present invention, the same being shown with the parts in the inert condition, such as the same would be during the periods of normal use of the protected building, when it is necessary to use the various doors and other protected openings;

Fig. 2 is a view similar to Fig. 1, but illustrating the system in its operative or set condition;

Fig. 3 is a plan view illustrating a modified form of the invention, of a more simplified character, but lacking certain of the desirable features shown in Figs. 1 and 2.

2

Fig. 4 is a view partly in perspective illustrating certain of the door operated switches used in the system; and

Fig. 5 is a view illustrating a modified form of a key operated setting lock employed in the system.

It should, of course, be understood that the description and drawings herein are illustrative merely, and that various modifications and changes may be made in the arrangements shown without departing from the spirit of the invention.

Referring now more particularly to Figs. 1 and 2 of the drawings, certain of the parts are mounted on a panel, the outline of which is indicated by dotted lines at 10. The panel is provided with a series of binding posts, A, B, C, D, E, F, and G, for convenience in wiring.

10 H is the battery or other source of direct current. The terminals of the battery H are respectively connected to the binding posts D and E by lines 11 and 12.

15 Mounted on the panel is a relay J, one end of the coil 13 of which is connected by line 14 to binding post A, and the other end of the coil 13 of which is connected by line 15 to the binding post B. The winding of the coil 13 of the relay J is of high resistance, of the order of about 2000 ohms. The armature 16 of the relay J is connected by line 17 to the binding post E to which one of the terminals of the battery H is connected.

20 For the proper operation of the system it is necessary that the armature 16, when in its released or free position will not be attracted to the pole of the relay coil even when the same is energized, but for the initial setting thereof said armature must be assisted to the magnetically held position, closer to the pole of the relay magnet, in a manner to be presently described. The armature 16 of the relay J is adapted, when released, to engage a contact screw 18 mounted in a bracket 19. The bracket 19 is connected by line 20 to one of the terminals of a buzzer 21. The other terminal of the buzzer 21 is connected by line 22 to the binding post G.

25 The winding of the coils of the buzzer 21 is such that the buzzer will not ordinarily be actuated by the normal amount of current passing through the line, but the same will be actuated under certain conditions of faults in the line, whereby an increased amount of current will be permitted to flow.

30 55 A shunt line 23 extends from line 20 to line

22 and is provided with a normally open switch 24 included therein.

The terminals of the buzzer 21 are connected to a resistance unit 25.

Mounted on the panel adjacent the relay J is a switch lock K, the bolt 30 of which is extended when the system is inert and retracted when the system is placed in the operative or set position.

The outer end of the bolt 30 of the lock K engages a spring arm 31 which carries a cylinder 32. The cylinder 32 serves to support a plunger 33, the outer end of which is adapted under tension of a spring 34 to contact the armature 16 of the relay J for the purpose of positioning the armature 16 close to the pole 35 of the relay magnet 13 when the bolt 30 of the switch lock K is extended so as thereafter to hold the armature while the relay coil remains energized.

The purpose of the above described device is to insure that the armature 16 of the relay J will be held within the range of the magnetic attraction of the pole 35 of the relay J for a sufficient period, as the bolt 30 of the switch lock is being retracted, until the main circuit is established, by the switching arrangement to be presently described, to energize the coil 13 of the relay J.

Adjacent the spring arm 31 which is controlled by the switch lock is a spring arm 36 insulated from spring arm 31 and the contact 37 at its free end which is adapted, when the bolt 30 of the switch lock K is retracted, to engage the contact 38 carried at the end of another spring arm 39 arranged adjacent thereto.

The spring arm 36 is connected by line 40 to the binding post D, which is connected to one of the terminals of battery H. The other spring arm 39 is connected by line 41 to binding post F.

One of the principal novel features of the present invention is the door operated switch M which is used as the means for effecting the final setting of the alarm system to operative condition. Said door operated switch M is shown in the lower part of each of wiring diagrams of Figs. 1 and 2, and is also illustrated in further detail in Fig. 3 of the drawings, the same comprising a plate member 50 adapted to be secured to a fixed portion of the building, such as the header of the door frame. Said plate 50 serves as a support for a cylinder 51 in which a sleeve member 52 is slidably mounted. A spring 53 within the cylinder 51 impels the sleeve member 52 to its outermost position as shown in Fig. 1 of the drawings.

In the sleeve member 52 a plunger 54 is mounted which is connected by a rod 55 to a contact disc 56 at the inner end thereof.

The contact disc 56 is adapted, when the door is open, to contact a spring arm 57 on one side, and to be seated in a notch 58 in a spring arm 59 on the other side of the supporting cylinder 51. The spring arm 59 also has an additional notch 60 in which the contact disc 56 is seated when the door is in its closed position.

The spring arm 57 is of such length that, when the door is in the closed position, the contact disc 56 will be separated therefrom, and no current will then pass through the spring arm 57. However, there is associated with the spring arm 57 another spring arm 61 which is adapted, when the door is closed, to be engaged by a contact screw 62 carried by a bracket member 63 secured to a portion of the door.

The door O is also provided with another bracket member or arm 64 which is adapted, as the door is closed, to first engage the sleeve member 52, and thereafter to engage the plunger 54.

to push the contact disc 56 to its innermost position when the door is closed.

The bracket member or arm 64 is connected to the bracket 63 by line 67 which may comprise a strip of metal foil disposed adjacent the edge of a glass panel, when such is used as a part of the door O.

The spring arm 61 which is adapted to be contacted by the screw 62 is connected by line 68 to the binding post A. The spring arm 59 which has the notches engaged by the contact disc 56 is connected by line 69, which may be one of the wires of the house circuit, to the binding post G.

A line 70 is connected at one end to the binding post B and at its other end to binding post C. Included in the lines 69 and 70 are the normally closed detector switches 71 which may be used in connection with the panels, doors and windows in the protected building, so as to break the circuit when any of the said switches are opened by reason of the opening of a door or window or other opening with which said switch is associated.

A line 72 runs from the binding post F to one terminal of the alarm bell R and the return line 73 runs from the other terminal of the alarm bell R to binding post G.

A resistance unit 74 is connected across the terminals of the alarm bell R.

30 A shunt line 79 having a normally closed switch 81 included therein runs from the line 41 which connects the spring arm 39 to the binding post F. Said shunt line 79 is connected to one of the terminals of the buzzer 80, the other terminal of which is connected by line 82 to binding post G. The coils of the buzzer 80 are also of low ohm winding, and this buzzer will be actuated whenever the alarm circuit is closed. A resistance unit 83, is connected across the terminals of the buzzer 80.

40 A line 84 extends from binding post C to one of the terminals of a buzzer 85 the other terminal of which is connected by line 86 to binding post E. The coils of the buzzer 85 are however of a higher ohm winding than those of the buzzers 21 and 80.

45 The winding of the coils of the buzzer 85 is such that the buzzer will not ordinarily be actuated by the normal amount of current passing through the line, but will be actuated under certain conditions of faults in the line whereby an increased amount of current will be permitted to flow.

50 A shunt line 87 extends from one of the terminals of the buzzer 85 and has included therein a normally open switch 88. The terminals of the buzzer 85 are also connected to a resistance unit 89.

55 The operation of the system and particularly the novel portions thereof may now be explained.

60 When the system is out of use as, for example, in the day time, during the usual and ordinary use of the protected building, the lock K is actuated, causing the bolt 30 of the lock to extend and bear against the spring arm 31 permitting the spring arm 36 to move so that the contact 37 thereof will be separated from the contact 38 which is carried by the spring arm 39.

65 As the spring arm 36 is connected by line 30 to binding post D, and thence by line 41 to one of the terminals of the battery H, it will be apparent that when the lock is thus operated, the supply of current from the battery will be cut off by the separation of the contacts 37 and 38, and the entire system will thus be rendered inert.

It will also be apparent that when the bolt 30 of the lock K is projecting outward, as above, the spring actuated plunger 33 carried by spring arm 31 will impinge against the armature 16 of the relay J thereby breaking the circuit which comes by line 17 to armature 16 and thence to contact screw 18, thereby preventing the current from passing through buzzer 21, or its resistance unit 25, or the switch 24 when said switch is closed.

One end of the coil 13 of the relay J is connected by line 14 through binding post A, and line 68 to the spring arm 57 of the door switch M, and thence through contact disc 56 to spring arm 59, to house line 69 which is connected to binding post G.

The other end of the relay coil is connected through line 15 to binding post B and through house line 70 to binding post C, and thence through the lines by which buzzer 85 is connected to binding post E. However, when the door O is closed, the circuit will be established from binding post A through line 68 and spring arm 61 of the door switch M, said spring arm 61 being adapted to be engaged by the contact screw 62 carried by the door, thus connecting the door panel line 67 into the circuit when the door is closed, it being noted that as the door is closed, the bracket 64 will first push the sleeve 52 inwardly until the bracket 64 encounters the plug 54 pushing the same inwardly to cause the contact disc 56 to disengage from the notch 58 of the spring arm 59, and thereafter be seated in the notch 60 of said spring arm. The circuit may thus be initially established when the door is open, and thereafter maintained when the door is closed.

When it is desired to put the system into operation the door is first opened to the position indicated in Fig. 1 of the drawings, after which the lock K is operated to cause the bolt 30 thereof to be retracted.

The retraction of the bolt 30 results in the making of the main circuit through the contacts 37 and 38 so that in setting the system, the operator will first cause the bolt 30 of the lock to be retracted and then as he passes on through the door the closing thereof will cause the detector circuit to be maintained and the line on the door panel, for the protection thereof, will be cut into said circuit.

However, the relay J will be energized prior to the making of the main circuit through the contacts 37 and 38, and will thus hold the armature 16 in the position shown in Fig. 1 of the drawings, whereby the circuit through the line 17 coming from binding post E to line 12 will be maintained open, and the alarm bell circuit thus rendered inert until the main circuit is broken either through one of the switches 71, in either of the house line 69 or 70, or by the opening of said circuit through the breaking of the line 67 which protects the door panel, or the cutting of any of the wires in said circuit.

Should the door O be improperly opened while the system is in the operative or set condition, the contact disc 56 will be retained in the notch 60 of the spring arm 59 until after the contact screw 52 has left the spring arm 61, and in this manner the detector circuit will be opened, and the coil 13 of the relay will thereby be de-energized, thus causing the alarm bell R to ring by reason of the armature 16 contacting the screw 19 and thus establishing the alarm circuit.

In Fig. 3 of the drawings there is shown a simplified arrangement of the circuits which,

however, will not have all the advantageous features of the arrangement shown in Figs. 1 and 2 of the drawings. As there shown, the same utilizes a panel 310 similar to the panel 10 of the other form and binding posts A³, B³, C³, D³, E³ and F³. In this arrangement the battery H³ is connected, similarly as in the other arrangement, to the binding posts D³ and E³. The relay J³ has a coil 313 connected at one end by line 314 to binding post A³. The other end of the coil 313 is connected by line 315 to binding post B³.

The binding post A³ is connected by line 368 which constitutes one of the detector or house lines to the door setting switch M³ which is of the same construction as the switch M in Fig. 1 of the drawings. The other end of switch M³ is connected by line 369 to binding post F³. The lines 368 and 369 are each provided with detector switches 371 at the doors, windows and other openings of the building to be protected.

The house line 370 is connected at one end to binding post B³, and at its other end to binding post C³, and also being provided with detector switches 371.

Binding post E³ is connected by line 372 to one of the terminals of the alarm bell R³, the other terminal of the alarm bell is connected by line 373 to binding post F³. In this form of the invention, binding post C³ is connected by line 384 to one of the terminals of the buzzer 385, the other terminal of which is connected by line 386 to binding post E³. The terminals of the buzzer 385 are also connected by a shunt line 387, having a switch 388 included therein.

The relay J³ is also provided with an armature 316 which is connected by line 317 to binding post D³. The armature 316 is adapted, when freed from the attraction to the pole 335 of the relay coil 313, to contact with the terminal 318 of the line 320. The terminal 318 of line 320 may, if desired, be like the contact screw 18 shown in Fig. 1 of the drawings.

The line 320 is connected to one of the terminals of a buzzer 321, the other terminal of which is connected by line 323 to binding post F³. A shunt 323 extends from line 320 to line 322, having a switch 324 included therein, adapted when the switch is closed to bypass the current around the buzzer 321.

The line 379 extends from binding post E³ to one of the terminals of a buzzer 380, and switch 381 included in said line.

The buzzer 380 has a resistance unit 389 connected in shunt across the terminals thereof, the buzzer 321 has a resistance unit 325 connected in shunt across the terminals thereof and the buzzer 380 has a resistance unit 383 connected in shunt across the terminals thereof.

There is also provided a setting lock K³, the bolt 330 of which is adapted when extended to hold the armature 316 of the relay out of engagement with the contact 318 thereof.

The operation of the arrangement shown in Fig. 3 of the drawings is substantially similar to that shown in Fig. 1 with the exception of the omission of the additional feature shown in Fig. 1 of the automatic opening of the circuit by the separation of the contacts 37 and 38, carried by the spring arms 36 and 39 respectively.

In Fig. 5 of the drawings there is shown a novel form of lock switch which is so constructed and arranged that the circuit will be maintained through the relay coil during the unlocking period. As there shown, the same comprises the provision of a spring member 91 so mounted to

be actuated by the inner end of the key when the same is inserted in the lock K or K³ as the case may be. Said spring member 91 is connected by line 92 to line 40 which is connected to spring member 36, and a portion of the lock housing is connected by line 94 to line 41 which is connected to spring arm 39.

I claim:

1. An electrical burglar alarm comprising a source of electrical energy, a primary circuit in which the same is included, a detector circuit having detector switches included therein, an alarm circuit having an alarm device included therein, a relay the coil of which is included in the detector circuit, an armature controlled by said relay adapted to close the alarm circuit when the relay coil is de-energized, a switch lock having a movable member adapted to hold the armature of the relay in circuit breaking position, a switch associated with said movable lock member adapted to open the primary circuit when the movable lock member is in position to hold the armature of the relay in its position to break the alarm circuit, means associated with the movable lock member for holding the armature in said alarm circuit breaking position until the switch in the primary circuit is closed and the relay coil thereby energized, a signal device in the alarm circuit and a signal device in the detector circuit, each of said signal devices in the alarm and detector circuits having a resistance unit in a shunt circuit whereby said signal device will be actuated in the event of faults in said alarm and detector circuits causing a variance of the current flow through said signal devices.

2. An electrical burglar alarm comprising a source of electrical energy, a primary circuit in which the same is included, a detector circuit having detector switches included therein, an alarm circuit having an alarm device included therein, a relay the coil of which is included in the detector circuit, an armature controlled by said relay adapted to close the alarm circuit when the relay coil is de-energized, a switch lock having a movable member adapted to hold the armature of the relay in circuit breaking position, a switch associated with said movable lock member adapted to open the primary circuit when the movable lock member is in position to hold the armature of the relay in its position to break the alarm circuit, means associated with the movable lock member for holding the armature in said alarm circuit breaking position until the switch in the primary circuit is closed and the relay coil thereby energized, and a door operated switch in the detector circuit adapted, when the door is closed, after the relay coil is energized, to complete the setting of the system, and thereafter to open the detector circuit in the event the door is opened.

3. An electrical burglar alarm comprising a source of electrical energy, a primary circuit in which the same is included, a detector circuit having detector switches included therein, an alarm circuit having an alarm device included therein, a relay the coil of which is included in the detector circuit, an armature controlled by said relay adapted to close the alarm circuit when the relay coil is de-energized, a switch lock having a movable member adapted to hold the armature of the relay in circuit breaking position, a switch associated with said movable lock member adapted to open the primary

circuit when the movable lock member is in position to hold the armature of the relay in its position to break the alarm circuit, means associated with the movable lock member for holding the armature in said alarm circuit breaking position until the switch in the primary circuit is closed and the relay coil thereby energized, and a door operated switch in the detector circuit adapted when the door is closed, after the relay coil is energized, to complete the setting of the system, and thereafter to open the detector circuit in the event the door is opened, said switch also being constructed and arranged to cut in a door protective circuit when the door is closed.

4. An electrical burglar alarm comprising a source of electrical energy, a primary circuit in which the same is included, a detector circuit having detector switches included therein, an alarm circuit having an alarm device included therein, a relay the coil of which is included in the detector circuit, an armature controlled by said relay adapted to close the alarm circuit when the relay coil is de-energized, a switch lock having a movable member adapted to hold the armature of the relay in circuit breaking position, a switch associated with said movable lock member adapted to open the primary circuit when the movable lock member is in position to hold the armature of the relay in its position to break the alarm circuit, means associated with the movable lock member for holding the armature in said alarm circuit breaking position until the switch in the primary circuit is closed and the relay coil thereby energized, a signal device in the alarm circuit and a signal device in the detector circuit, each of said signal devices in the alarm and detector circuits having a resistance unit in a shunt circuit whereby said signal device will be actuated in the event of faults in said circuits causing a variance of the current flow through said signal devices, and a door operated switch in the detector circuit adapted when the door is closed, after the relay coil is energized, to complete the setting of the system, and thereafter to open the detector circuit in the event the door is opened.

5. An electrical burglar alarm comprising a source of electrical energy, a primary circuit in which the same is included, a detector circuit having detector switches included therein, an alarm circuit having an alarm device included therein, a relay the coil of which is included in the detector circuit, an armature controlled by said relay adapted to close the alarm circuit when the relay coil is de-energized, a switch lock having a movable member adapted to hold the armature of the relay in circuit breaking position, a switch associated with said movable lock member adapted to open the primary circuit when the movable lock member is in position to hold the armature of the relay in its position to break the alarm circuit, means associated with the movable lock member for holding the armature in said alarm circuit breaking position until the switch in the primary circuit is closed and the relay coil thereby energized, a signal device in the primary circuit adapted to be actuated when the alarm device is actuated, a signal device in the alarm circuit and a signal device in the detector circuit, each of said signal devices in the alarm and detector circuits having a resistance unit in a shunt circuit whereby said signal device will be actuated in the event of faults in said alarm and detector

circuits causing a variance of the current flow through said signal devices, and a door operated switch in the detector circuit adapted when the door is closed, after the relay coil is energized, to complete the setting of the system, and thereafter to open the detector circuit in the event that the door is opened.

6. An electrical burglar alarm comprising a source of electrical energy, a primary circuit in which the same is included, a detector circuit having detector switches included therein, an alarm circuit having an alarm device included therein, a relay the coil of which is included in the detector circuit, an armature controlled by said relay adapted to close the alarm circuit when the relay coil is de-energized, a switch lock having a movable member adapted to hold the armature of the relay in circuit breaking position, a switch associated with said movable lock member adapted to open the primary circuit when the movable lock member is in position to hold the armature of the relay in its position to break the alarm circuit, means associated with the movable lock member for holding the armature in said alarm circuit breaking position until the switch in the primary circuit is closed and the relay coil thereby energized, a signal device in the primary circuit adapted to be actuated when the alarm device is actuated, a signal device in the alarm circuit and a signal device in the detector circuit, each of said signal devices in the alarm and detector circuits having a resistance unit in a shunt circuit whereby said signal device will be actuated in the event of faults in said alarm and detector circuits causing a variance of the current flow through said signal devices, and a door operated switch in the detector circuit adapted when the door is closed, after the relay coil is energized, to complete the setting of the system, and thereafter to open the detector circuit in the event the door is opened, said switch also being constructed and arranged to cut in a door protective circuit when the door is closed.

7. An electrical burglar alarm comprising a source of electrical energy, a primary circuit in which the same is included, a detector circuit having detector switches included therein, an alarm circuit having an alarm device included therein, a relay the coil of which is included in the detector circuit, an armature controlled by said relay adapted to close the alarm circuit when the relay coil is de-energized, a switch lock having a movable member adapted to hold the armature of the relay in circuit breaking position, a switch associated with said movable lock member adapted to open the primary circuit when the movable lock member is in position to hold the armature of the relay in its position to break the alarm circuit, means associated with the movable lock member for holding the armature in said alarm circuit breaking position for energizing the relay coil prior to and until the switch in the primary circuit is closed, said means comprising a shunt circuit around the switch in the primary circuit and means included in said shunt circuit to close the same upon insertion of a key in the switch lock.

8. An electrical burglar alarm comprising a source of electrical energy, a primary circuit in which the same is included, a detector circuit having detector switches included therein, an alarm circuit having an alarm device included therein, a relay the coil of which is included in

the detector circuit, an armature controlled by said relay adapted to close the alarm circuit when the relay coil is de-energized, a switch lock having a movable member adapted to hold the armature of the relay in circuit breaking position, a switch associated with said movable lock member adapted to open the primary circuit when the movable lock member is in position to hold the armature of the relay in its position to break the alarm circuit, means associated with the movable lock member for holding the armature in said alarm circuit breaking position for energizing the relay coil prior to and until the switch in the primary circuit is closed, said means comprising a key controlled shunt circuit around the switch in the primary circuit.

9. In an electrical burglar alarm system including a detector circuit having detector switches therein, a door operated switch in said detector circuit adapted to complete the setting of the system, said switch comprising a pair of spring arms, a contact member adapted to contact both of said arms and thereby maintain the circuit when the door is open, said contact member being movable to a position to break the contact with one of said arms when the door is closed, an auxiliary contact arm electrically connected to said last mentioned arm adapted to be engaged when the door is closed by a contact member carried by the door, another member carried by the door adapted to actuate the movable contact member when the door is closed and to establish an electrical connection therewith, an electrical connection between the members carried by the door, and means for restraining the movement of the movable contact member when the door is opened until the contact member carried by the door is separated from the auxiliary contact arm.

10. In an electrical burglar alarm system including a detector circuit having detector switches therein, a door operated switch in said detector circuit adapted to complete the setting of the system, said switch comprising a pair of spring arms, a contact member adapted to contact both of said arms and thereby maintain the circuit when the door is open, said contact member being movable to a position to break the contact with one of said arms when the door is closed, an auxiliary contact arm electrically connected to said last mentioned arm adapted to be engaged when the door is closed by a contact member carried by the door, another member carried by the door adapted to actuate the movable contact member when the door is closed and to establish an electrical connection therewith, an electrical connection between the members carried by the door including a protective line positioned marginally on a panel of the door, and means for restraining the movement of the movable contact member when the door is opened until the contact member carried by the door is separated from the auxiliary contact arm.

BURNETT MENKIN.
